J. B. HAGERTY

FOLDING MACHINE ATTACHMENT

Filed May 3, 1923

INVENTOR.
BERNARD HAGERTY

BY Sheffield & Bedell
This ATTORNEYS.

UNITED STATES PATENT OFFICE.

JOHN BERNARD HAGERTY, OF WAPPINGERS FALLS, NEW YORK.

FOLDING-MACHINE ATTACHMENT.

Application filed May 3, 1923. Serial No. 636,422.

To all whom it may concern:

Be it known that I, JOHN BERNARD HAGERTY, a citizen of the United States, residing at Wappingers Falls, county of Dutchess, State of New York, have invented a new and useful Folding-Machine Attachment, of which the following is a specification.

My invention relates to an attachment for machines used for the purpose of folding cloth or fabrics, such as cotton fabrics. Some of the objects of my invention are to provide means whereby cloth folding machines may be used for folding doubled cloth; to provide means for passing the doubled cloth from a source of supply, such as a roll or pile, to the folding mechanism in such manner as to prevent creasing of the cloth; and also to provide means whereby this is done so efficiently that the amount of cloth folded in a given time may be considerably greater than has been possible by means of prior arrangements.

A further object of my invention is to provide folding means for doubled cloth, which shall obviate the wiring now required.

The preferred form of apparatus according to my invention is illustrated in the drawing, in which—

Figure 1 is an end elevation of such apparatus, part of the cloth being torn away and other parts being broken away for the sake of clarity;

Figure 2 is a side elevation looking from the right in Figure 1; and

Figure 3 is a cross-section of the guide member 13, on the line *a—a* of Figure 2.

Similar numerals refer to similar parts in both of the views.

According to the preferred form of my invention, a roll of doubled cloth 1 is placed in the bracket 2 in such manner as to be free to revolve therein. The edge of the cloth which is folded is placed toward the left in Fig. 1 or at the back of Fig. 2.

Above the roll of cloth 1 is a pair of power nip rolls 3, 4 which draw the cloth from the roll 1 and drop it into the curved, hanging pan 5, as at 6. This pan may be made of sheet zinc or other material that will not stain the cloth. The speed of the rolls 3, 4 is controlled so that there is always a surplus of cloth lying in the pan 5; the purpose of this is to furnish an ample supply of cloth for the intermittent pull of the folding mechanism.

Upon leaving the pan 5, the cloth passes over an elevated platform 7, placed above the frame 8 of the folding machine. The platform 7 may be made of wood or other rigid material and is provided with an up-standing flange 9 which is placed at the left of the platform when viewed as in Fig. 1; the folded edge of the cloth, as it passes over the platform, is guided by this flange. Leaving the platform 7, the cloth passes between upright supports 10, 10 and over an idle roll 11, placed in the vertical plane of the mid-point of travel of the hooker blade of the folding mechanism, and above such mechanism. To insure the cloth's passing over the roll 11 without bunching or creasing, a weight 12 is flexibly suspended above the roll 11 and so placed that it bears against the forward face of the roll by gravity. The weight 12 may be made of wood or heavy cardboard and is surfaced with heavy canvas or other material which is soft and yet heavy enough to stand the abrasive action of the passing cloth. The friction or rubbing pressure exerted by the weight 12 against the cloth as it passes between the weight and the roll operates to keep the cloth under a sufficient amount of tension to avoid bunching or creasing which would otherwise result from the intermittent and jerky pull of the folding mechanism.

In the vertical plane of the forward face of the roll 11, I provide a sword-like guide-member 13 supported from one of the uprights 10 by an adjustable arm 14. The cloth is divided as it passes over the member 13, the interior of the fold side passing along the beveled edge 15 thereof; the top and bottom edges of the guide-member are also beveled, as shown at 16, 17, to facilitate the passage of the cloth thereover. Thus the member 13 operates to guide and smooth out the fold of the doubled cloth.

Placed beneath the guide 13 is the usual folding mechanism consisting of the power-driven crank-wheel 18, connecting rod 19, pivoted hooker arm 20, and hooker blade 21. As the manner of operation of this mechanism is well known to those skilled in the art, and as it forms no part of my invention, no further description thereof is deemed to be necessary.

It will be evident to those skilled in the art, that the combination of platform and flange, 7 and 9, roll and weight, 11 and 12, and guide member 13, make it possible for

the folding mechanism to operate more quickly than has heretofore been possible without creasing or bunching the cloth.

The pull on the cloth exerted by the hooker blade of the folding mechanism is intermittent and jerky; therefore, means must be provided to insure the cloth's being delivered to the hooker blade free from creases. Such means, in the preferred form shown, consist of the platform 7, which operates to smooth out the cloth as it is pulled out of the pan 5, this operation being assisted by the weight of the cloth hanging from the edge 22 of the pan; further, the idle roll 11 and the co-operating weight 12, by virtue of pressure on the cloth as it passes over the roll, hold the same under sufficient tension to prevent the cloth's becoming slack or overrunning itself; lastly, any inequalities at the fold side of the cloth are evened out by means of the beveled edge 15 of the guide member 13.

I recognize that various modifications in detail and in arrangement of parts of my apparatus may be made by those skilled in the art without departing from the scope of my invention, and I therefore desire protection for all such modifications as come within the scope of the appended claims.

It will be evident also that according to my invention all necessity for wiring is done away with.

Having described the preferred form of my invention, what I claim is:

1. In a machine for folding doubled cloth, the combination of a hooker arm, a guide member above said arm arranged to normally contact with the inner surface of the crease in the cloth being folded, means for guiding the doubled cloth to said member on its way to said hooker arm, and means for maintaining tension on the cloth being folded.

2. In a machine for folding doubled cloth, the combination of a hooker arm, a guide member above said arm designed to contact with the inner surface of the cloth being folded, said guide member being beveled and having its thin edge against the cloth, means for guiding the double cloth to said member on its way to said hooker arm, and means for maintaining tension on the cloth being folded.

3. In a machine for folding doubled cloth, the combination of a hooker arm, a guide member above said arm contacting with the inner surface of the cloth being folded, said member being beveled and having its thin edge against the cloth, said member also being beveled at the ends pointing in the direction of the travel of the cloth, means for guiding the doubled cloth to said member on its way to said hooker arm, and means for maintaining tension on the cloth being folded.

4. An attachment for a cloth-folding machine comprising in combination a smooth-surfaced platform over which the cloth passes, a roll in proximity to the discharge edge of said platform, and means for exerting a rubbing pressure against the cloth where it passes over said roll. ⁷⁰

5. In apparatus for folding doubled cloth, the combination comprising a smooth-surfaced platform over which the cloth passes, ⁷⁵ said platform having an upstanding flange to guide one edge of the cloth, a roll in proximity to the discharge edge of said platform, means for exerting a rubbing pressure against the cloth where it passes over said roll, and a member having a beveled edge lying in the line of travel of the cloth and so placed that the interior of the folded edge of the cloth contacts therewith. ⁸⁰

6. In apparatus for folding doubled cloth, the combination comprising a smooth-surfaced platform over which the cloth passes, ⁸⁵ said platform having an upstanding flange to guide one edge of the cloth, a roll in proximity to the discharge edge of the platform, and means for exerting a rubbing pressure against the cloth where it passes over said roll. ⁹⁰

7. In apparatus for folding doubled cloth, the combination comprising a smooth-surfaced, sloping platform over which the cloth passes, ⁹⁵ said platform having an upstanding flange to guide the folded edge of the cloth, a roll over which the cloth passes, a flexibly-supported weight for exerting pressure ¹⁰⁰ against the cloth where it passes over said roll, and a member having a beveled edge lying in the line of travel of the cloth and so placed that the interior of the folded edge of the cloth contacts therewith. ¹⁰⁵

8. In apparatus for folding doubled cloth, the combination comprising a smooth-surfaced platform over which the cloth passes, a roll over which the cloth passes, means for exerting a rubbing pressure against the cloth ¹¹⁰ where it passes over the roll, and a member having a beveled edge lying in the line of travel of the cloth and so placed that the interior of the folded edge of the cloth contacts therewith. ¹¹⁵

9. In apparatus for folding doubled cloth, the combination comprising a smooth-surfaced platform over which the cloth passes, means in proximity to the discharge edge of the platform for retarding the free movement of the cloth, and a member having a beveled edge lying in the line of travel of the cloth and so placed that the interior of the folded edge of the cloth contacts therewith. ¹²⁰

10. In apparatus for folding doubled cloth, the combination comprising a smooth-surfaced platform over which the cloth passes, means for retarding the free movement of the cloth, and a member for guid- ¹²⁵

ing the inner surface of the folded edge of the cloth.

11. In apparatus for folding doubled cloth characterized by a reciprocating hooker blade, the combination comprising an elevated, sloping, smooth-surfaced platform over which the cloth passes, means in proximity to the discharge edge of the platform for retarding the free movement of the cloth, said means being placed in the vertical plane through the mid-point of travel of the hooker blade and above the same, and a member lying substantially in said plane below said means and having a beveled vertical edge so placed that the interior of the folded edge of the cloth contacts therewith.

12. In apparatus for folding doubled cloth, the combination comprising means for guiding the outer surface of the folded edge of the cloth, a roll co-operating with said means, means for exerting a rubbing pressure on the cloth where it passes over said roll, a member for guiding the inner surface of the folded edge of the cloth, and means for folding the cloth.

13. In apparatus for folding doubled cloth, the combination comprising a means for guiding the outer surface of the folded edge of the cloth, a roll co-operating with said means, a flexibly-supported weight for exerting a rubbing pressure against the cloth where it passes over said roll, a member for guiding the inner surface of the folded edge of the cloth, and means to fold the cloth.

14. In apparatus for folding doubled cloth, the combination comprising a means

for guiding the outer surface of the folded edge of the cloth, a roll co-operating with said means, means for exerting a rubbing pressure against the cloth where it passes over said roll, a member having a beveled edge lying in the line of travel of the cloth and so placed that the interior of the folded edge of the cloth contacts therewith, and means for holding the cloth.

15. In apparatus for folding doubled cloth, the combination comprising a smooth-surfaced platform over which the cloth passes, said platform having an upstanding flange to guide the folded edge of the cloth in the line of travel thereof, a roll in proximity to the discharge edge of said platform, means for exerting a rubbing pressure against the cloth where it passes over said roll, and a member having a beveled edge lying in the line of travel of the folded edge of the cloth and so placed that the inner surface of the crease of the cloth contacts therewith.

16. In apparatus for folding doubled cloth, the combination of a reciprocating hooker blade, means comprising a roll and a flexibly supported weight for exerting a rubbing pressure against the cloth where it passes over said roll, said means being placed in the vertical plane through the mid-point of travel of the hooker blade and above the same, and a guide member for the inner surface of the folded edge of the cloth located in said plane between said means and the hooker blade.

JOHN BERNARD HAGERTY.
